UNITED STATES PATENT OFFICE.

ALBERT LESLIE OLIVER, OF OAKLAND, CALIFORNIA, ASSIGNOR TO CALIFORNIA CAP COMPANY, OF OAKLAND, CALIFORNIA, A CORPORATION.

ELECTRIC BLASTING-CAP.

1,378,269.

Specification of Letters Patent. Patented May 17, 1921.

Application filed January 27, 1920. Serial No. 354,435.

To all whom it may concern:

Be it known that I, ALBERT LESLIE OLIVER, a citizen of the United States, residing at Oakland, in the county of Alameda and State of California, have invented certain new and useful Improvements in Electric Blasting-Caps, of which the following is a specification.

In delay electric blasting caps as at present universally used there is provided a member or means removably associated with one end of the device for filtering or arresting the flame caused by the igniting of the exploder whereby the flame is prevented from prematurely igniting the charge to be exploded.

The present invention has for its principal object to provide an exploder wherein this removable end feature or filtering cap is dispensed with and a construction is provided having a self-contained filtering medium whereby the same is capable of functioning to extinguish a flame or spark, and which is so constructed and arranged to be ignited by the action of an electric current. A further object is to provide a construction wherein the flame or sparks emitted by the burning fuse portion of the igniter will not come in contact with the explosive charge but will permit the products of combustion arising from the burning fuse powder to escape without liability of setting-off or prematurely exploding the main explosive charge, thereby providing an exploder which is particularly adapted for employment in mining and blasting operations, especially where black powder is used and one which is capable of use in coal mines and whereby the liability of the ignition of the gases produced by the blast of a previous round is eliminated.

With the above mentioned and other objects in view the invention consists in the novel construction and combination of parts hereinafter described, illustrated in the accompanying drawings, and set forth in the claims hereto appended, it being understood that various changes in the form, proportion, size and minor details of construction within the scope of the claims may be re-

sorted to without departing from the spirit or sacrificing any of the advantages of the invention.

To comprehend the invention reference is directed to the accompanying drawings, 55 wherein,

Figure 1 is a vertical sectional view of the preferred embodiment of my invention.

Fig. 2 is a transverse sectional view taken 60 on line 2—2 of Fig. 1.

Fig. 3 is a view of the upper end of a modified form of construction.

Fig. 4 is a transverse sectional view taken 65 on line 4—4 of Fig. 3.

Referring to the drawings wherein like characters of reference designate corresponding parts, 1 indicates a suitable time fuse of any desired material provided in its center with the open ended bore 2, which is filled with powder 3 forming a suitable 70 powder train. Secured in any suitable manner to the upper end of the time fuse 1, as by crimping at 4, is, the lower end of a metallic shell 5, the upper portion of which is preferably enlarged providing a chamber 75 6 for containing an igniting compound or inflammable substance 7. The chamber 6 is provided with an upper wall 8 which is the lower surface of a suitable plug 9 positioned within the metallic shell and preferably of 80 a diameter smaller than the interior of the shell to provide a space 10 surrounding the plug. Above the plug the interior of the shell is provided with a body 11, of any suitable filtering material, such as asbestos 85 or the like, and the same is held between the upper surface of the plug 9 and the lower surface of a suitable closure plug 11', preferably of sulfur which is positioned in the upper end of the metallic shell. The plug 90 11' is preferably held in position by the crimped portions 12, and is provided with the centrally disposed vent 13, the lower end 95 of which is normally closed by a wad or dis- placing member 14, which is held in position by a grease or wax filling 15 in the upper end of the bore 13. Electric conductors 16 extend downwardly through the plug 11', filtering material 11 and plug 9 into the chamber 6 where the ends thereof 100

are connected by a resistance coil 17 which passes through the body 7 of igniting compound. In this construction, it will be apparent that the filtering material 11 is self-contained within a metallic shell and is positioned therein between the vent opening 13 and the chamber 6, whereby the gases generated on the ignition of the inflammable substance 7 must pass through the filtering material prior to escaping from the interior of the shell 5. This construction prevents the use of the device with the filtering material disconnected or removed therefrom which is often the case when the devices for this purpose as now on the market are used by inexperienced persons, and with often great damage and premature explosion to the blast.

To the lower end of the fuse 1 is preferably secured by crimping as at 18, a metallic cap 19 which contains a suitable fulminating compound such as fulminate of mercury, and the joint connections between the metallic cap 19 and metallic shell 5 and the fuse 1 are protected by a suitable waterproof compound or shell 20, which overlies the terminal edges of the respective shell and cap, as illustrated in Fig. 1.

The action of the present exploder is similar to those already on the market, but for clearness of description the same operates as follows:

The device being assembled as in the drawings with either the metallic cap 19 and its associated parts secured to or eliminated from the time fuse 1, depending on the type of blasting powder used, current is supplied to the conductors 16. The current passing through the conductors 16 heats the resistance coil 17 causing an explosion of the igniting or inflammable compound 7, the gases from which due to being confined within the shell 5 expand and pass through the air passages 10 surrounding the plug 9, pass through the filtering material 11 and act on the ball 14 forcing the same upwardly into the bore 13 and displacing the grease or wax filling 15 in said bore 13, thus providing an opening from the chamber 6 to the exterior of the metallic shell 5, for the gases, but it will be readily understood that the gases in passing from the chamber 6 to the exterior of the shell 5 must pass through the filtering material before passing through the bore 13. The explosion of the igniting compound ignites the powder train 3, which burns for any given time depending on the length of the fuse 1, and when the same burns to the lower end of the fuse, it ignites the fulminating compound within the metallic cap 19. Should this cap 19 and fulminating compound be dispensed with, the powder train ignites the material associated with the lower end of the fuse 1.

In the construction illustrated in Fig. 3 it

will be observed that a solid plug 21, preferably of sulfur, is positioned to close the upper end of the shell 5, and that the shell immediately below the lower end of the plug is provided with the vents or openings 22, communicating with the inner end of the filtering material which is positioned within the shell, as in the construction illustrated in Fig. 1. To firmly close the vents or openings 22, the sleeve 20 at its upper end is extended a considerable distance over the wall surface of the shell 5, and at its terminal upper end 23 overlies said ports or openings 22. In this case, the explosion of the igniting compound causes a breaking away of the sleeve at its upper end 22 completing the opening in the ports or channels from the interior of the shell to the exterior thereof.

It will be apparent that the present construction provides a safe and simple electric fuse igniter which will not emit sparks or flame, as the gases of combustion are filtered prior to passing from the interior of the fuse, and one where it is impossible to use the construction with the filtering material eliminated therefrom, as it is contained and concealed within the fuse structure.

Having thus described my invention what I claim is:

1. The combination with a fuse, a tubular metallic shell member secured at one end thereto, an inflammable substance contained within said shell for igniting said fuse, a plug member for closing one end of said shell, one of said members being provided with a normally closed vent for permitting the escape of generated gases from within said shell and adapted for opening on the igniting of said inflammable substance, a filtering material within the shell intermediate the inflammable substance and said vent opening, and electric means extended into said inflammable substance for igniting the same.

2. The combination with a fuse, a tubular metallic shell positioned over and secured to one end thereof, an inflammable substance contained within said shell for igniting said fuse, a plug for closing the open end of the shell, a plug held within the shell in spaced relation to the walls thereof and adjacent to said inflammable substance and with said shell providing a chamber, a filtering medium within said chamber between said plugs, electric means extended into said shell for igniting said inflammable substance, and a normally closed vent formed in one wall of said chamber and through which the products of combustion escape from said shell after passing through said filtering material.

3. The combination with a fuse, a tubular shell secured thereto, an inflammable substance contained within the shell, a plug within the shell adjacent to said inflammable substance and formed to permit a space be-

tween its wall and the wall of said shell, a
plug held within the shell in spaced relation
to said first plug and provided with a tubu-
lar bore, a wad for closing said bore, dis-
placeable means for holding said wad within
said bore, electric conductors passing through
said plugs, a resistance coil connecting the
inner ends of said conductors and extending
into said inflammable material and a body of

filtering material within said shell between 10
said plugs.

In testimony whereof I have signed my
name to this specification in the presence of a
subscribing witness.

ALBERT LESLIE OLIVER.

Witness:

HARRY A. TOTTEN.
